UNITED STATES PATENT OFFICE.

HERMAN L. KUTTER, OF HAMILTON, OHIO, ASSIGNOR OF ONE-HALF TO WALTER D. RANDALL, OF CINCINNATI, OHIO.

PAPER MACHINERY.

Application filed August 29, 1925. Serial No. 53,301.

This invention relates to paper-making machinery and more particularly to paper-making machinery of the Fourdrinier type in which a traveling endless forming wire 5 is mounted upon a breast-roll at the front end of the machine and a suction roll at the rear of the machine, there being intermediate the breast-roll and the suction roll a table roll frame and a suction box frame 10 over which the forming wire is adapted to move.

One of the principal objects of the invention is to provide a frame carrying table-rolls thereon, said frame being mounted independently of the breast-roll and movable out of alignment therewith to permit ready removal of the forming wire.

Another object is to provide a normally stationary frame for the table-rolls in association with a shakable breast-roll which is adapted to impart a shaking movement to the forward end of the forming wire.

Still another object is to provide a paper forming section with a table-roll frame and a suction-box frame, both of which are bodily movable out of alignment with the forming wire to facilitate removal of the wire.

Other objects and advantages of the present invention will be apparent from the following description when taken in connection with the accompanying drawings in which:

Fig. 1 is a side elevation of the breast-roll end of a forming section of the Fourdrinier type embodying the present invention;

Fig. 2 is a continuation of Fig. 1 showing the suction box end of the forming section;

Fig. 3 is an enlarged side elevational view 40 of the breast-roll end of Fig. 1; and

Fig. 4 is a plan view of the suction-box frame shown in Fig. 2.

In the drawings 20 designates an endless forming wire which is mounted at its forward end on breast-roll 21 and at its rearward end upon suction roll 22, as is usual in paper-making machines of this type. The wire, which is endless, is adapted to receive paper-making stock or pulp from the

flow box 23 through an orifice or inlet 24, the height opening of the inlet being adjustable by mechanism 25 which, because it is of usual construction and forms no part

of the present invention, need not be described in detail. The paper-making stock which flows upon the wire 20 is carried by the wire in succession over the table rolls 26 and the suction boxes 27, this movement of the forming wire being indicated by the arrow A in Figs. 1 and 2. The formed sheet of paper is removed from the wire at the end of the forming section by mechanism not shown, and the forming wire is returned to the breast-roll as indicated by the arrows B in Figs. 1 and 2, the forming wire passing underneath the suction-box frame and the table-roll frame, suitable guide rolls being provided for the wire at 29, and a wire tensioning roll being provided at 30.

Referring particularly to Figs. 1 and 3, the breast-roll 21 is journaled in the block 33 having bearings at its opposite ends to receive the shaft 34 of the breast-roll. The block 33 having an apron 35 formed at its upper end is guided for vertical movement in breast-roll frame 36 in which it is carried, suitable adjusting means being provided at 37 for adjusting the top of the apron 35 to the same level as the top of the table rolls 26. The breast-roll frame 36 is mounted upon uprights 38 which have pivoted or rocking connection with the breast-roll frame 36 at their upper ends, and with the floor bearings 39 at their lower ends, whereby the breast-roll frame 36 and breast-roll 21 may be given a rocking or shaking movement in the direction of the longitudinal axis of the breast-roll, that is, in a direction transverse to the movement of the traveling wire 20. The construction of mechanism for transmitting shaking movement to the breast-roll 21 is generally old in the art, but I prefer to use the form of support and shaking mechanism described and claimed in my co-pending application S. N. 682,684, filed December 26, 1923. This rocking and shaking mechanism forms no part of the present invention and reference to said co-pending application is therefore deemed a sufficient disclosure.

The bearing for the breast-roll has a removable section or cap 45 which may be taken off to permit the removal of the breast-roll from its bearings when it is desired to disassemble the apparatus or to temporarily

- remove the breast-roll for the purpose of removing or replacing the forming wire. Each of the removable bearing sections 45 carries a pivoted arm 46 having an upwardly opening slot to receive the pivot shaft 47 of the doctor 48. The arm 46 may be adjusted vertically to vary the position of the doctor 48 upon the surface of the breast-roll 21.
- 10 The table rolls 26 are journaled in any suitable manner upon the table-roll frame 50, which also carries beneath the table rolls the save-alls 51 and save-all pans 52. A trough 53 is carried underneath the table rolls nearest to the breast roll, such trough being of such length as to receive material removed from the breast-roll 21 by the doctor 48, and to carry the same to one of the save-all pans 52. The trough 53 is loosely mounted so that it may be withdrawn to a position entirely underneath the table rolls at certain times, as for example when it is desired to remove the bearing cap 45 and doctor 48. The frame 50 together with the 25 table rolls 26 and save-alls 51, is normally stationary during operation of the paper-making machine, but it is mounted in such wise as to be movable laterally out of alignment with the forming wire 20 so as to 30 facilitate the ready removal of the forming wire for purpose of replacement, as will be hereinafter more fully explained. To enable such lateral movement of the frame 50, the latter is provided with anti-friction rolls 35 55 adapted to ride upon the transverse tracks 56 mounted upon the pedestals or supports 57. As clearly shown in Fig. 1, the frame 50, with the parts carried thereon, is entirely independent of the breast-roll 21 and 40 its support, and as a consequence it may be rolled sidewise upon the tracks 56 out of alignment with the forming wire 20 and the breast-roll parts.
- The suction boxes 27 are carried by a suction box frame 60 comprising side rails 61 and 62 between which rails the forming wire is adapted to pass over the suction boxes as best shown in Fig. 4. The suction box frame 60, like the table-roll frame 50, is supported so that it may be moved laterally out of alignment with the forming wire so as to facilitate ready removal of the forming wire. The supporting means for the suction-box frame comprises supports or pedestals 63 having transverse rails or tracks 64 to receive the roller bearings 65 which are journaled in trucks 68 and 69 carrying the suction-box frame.
- During the normal operation of the paper forming section, in which the forming wire travels continuously at a high speed over the suction box, there is a tendency for the longitudinal strands of wire of which the forming wire is made, to wear grooves or 65 lines in the upper surface of the suction boxes thereby causing not only undue wear of the suction boxes but also increasing the friction between the forming wire and the suction boxes, such friction of course being detrimental to the life of the forming wire and introducing resistance to the movement thereof. To overcome this objection, means is provided for imparting to the suction-box frame an oscillatory movement transverse to the direction of travel of the forming wire, so that the longitudinal strands of wire of which the forming wire is made up, are caused to ride over various parts of the suction-box surface and to wear the same evenly.
- As best shown in Fig. 4, the suction-box frame 60 is pivotally connected at one end with one of the blocks or trucks 68 which carries the roller 65. The pivotal connection between the truck 68 and the suction-box frame may be secured by a pivot pin 67 associated with the side rails 61 or some other convenient part of the suction-box frame. The other end of the suction-box frame may be given a lateral back and forth movement upon the truck 69, the suction-box frame moving about the pin 67 as a pivot. For oscillating the suction-box frame upon the truck 69 the latter may be provided with a transverse shaft 75 carrying a pulley 76 90 on one end thereof, which pulley may be connected through a suitable driving connection with a motor or other prime mover 77, the driving connection herein shown comprising a housing 78 containing speed reducing gearing, a pulley 79, and a driving belt 80 connected between the pulleys 76 and 79. A beveled gear 83 carried by the shaft 75 cooperates with beveled gear 84 which latter is connected with a bearing 100 plate 85 having bearing in the upper surface of the truck 69. An eccentric pin 87 carried by the bearing plate 85 cooperates with slot 88 in the side frame member 61 to impart an oscillating movement to the 110 suction-box frame upon rotation of the shaft 75 and gears 83 and 84. The suction-box frame may be oscillated as rapidly as desired, but it is found that satisfactory results are obtained by oscillating at a very 115 low rate, as for example one oscillation in five or ten minutes. The form of mechanism herein shown for oscillating the suction box frame does not interfere with the bodily movement of the suction-box frame to a position out of alignment with the forming wire whenever it is desired to replace the latter. The prime mover 77 and the speed reducing gearing are mounted below the suction-box frame in such a position that the 120 frame may move over these parts. The remaining parts of the oscillating mechanism are movable with the truck 69 and suction-box frame 60, except the belt 80 which may be removed from its pulleys before under- 130

taking the bodily movement of the suction-box frame upon its tracks 64.

Preparatory to the removal or replacement of the forming wire 20, the tension roll 30 is removed from its normal tensioning position and supported upon the hook bearings 90 carried at the rear of the table-roll frame 50. Next, the breast-roll 21 is removed from its bearings and likewise supported from the table-roll frame 50, but at its forward end. For this purpose the forward end of the table-roll frame is provided with loops of rope or other similar material 91 which are adapted to be looped over the 10 projections 92 extending from the ends of the breast-roll shaft. Before removing the breast-roll 21 from its bearings in the block 33, the projections 92 of the breast-roll shaft are engaged by eye plates or hooks 93 connected with the chains 94 of hoisting apparatus 95 which may be of usual conventional construction. The hoisting apparatus being operated to hold the breast-roll in its bearings as shown in full lines in Fig. 1, the 15 bearing section or cap 45 is removed together with the doctor 48 and its associated parts 46 and 47, the trough 53 having first been withdrawn so as not to interfere with the operation. Temporary guiding means 20 or tracks 100 are connected between the breast-roll frame 36 and the pedestals 57. Now, by operating the hoisting mechanism 95, the breast-roll 21 may be lowered or guided along the guide rails 100 until the 25 breast-roll reaches a position such that the supporting means 91 may be engaged with the shaft projections 92. Further lowering of the breast-roll 21 may be continued until the breast-roll, supported by the supporting 30 means 91, swings clear of the guides 100, this position being indicated in dotted lines in Fig. 1. The guides 100 are now removed, and the table roll frame 50 carrying the tension roll 30 and breast-roll 21, is now ready 35 to be moved laterally out of the loop formed by the forming wire 20. It is to be observed however that the transference of the tension roll 30 and the breast roll 21 from their normal positions to their dotted line 40 positions suspended from the table-roll frame 50 has resulted in a loosening or slackening of the forming wire 20 as indicated by the dot and dash lines in Figs. 1 and 2. Bars or rods are inserted through the loop of 45 the forming wire 20 as indicated at 101, to hold the same clear of the table roll 50 during lateral movement of the latter, and the same operation is repeated when the suction-roll frame 60 is to be moved laterally 50 to a position out of alignment with the forming wire.

It will be apparent from the foregoing that the machine herein disclosed is especially adapted for the removal and replacement of the forming wire. It has already

been explained how the table roll frame 50 carrying with it the tension roll 30 and breast roll 21, may be rolled laterally out of the loop of the forming wire; also how the suction-box frame may be moved laterally out of the loop of the forming wire. The old forming wire 20 may now be readily removed, and after engaging the new forming wire with the suction roll 22, an operation which is comparatively simple to men skilled in the art, the new forming wire 20 may be extended along the length of the machine, after which the parts may be reassembled or repositioned by a process which is the reverse of the one described above for removing the forming wire.

During the normal operation of a paper-making machine embodying the present invention, the table roll frame 50 together with the table rolls 26 and other parts carried thereon, is maintained in stationary position upon its tracks 56. At the same time an oscillating or shaking movement is given to the breast-roll support and to the breast-roll 21 and doctor 48 carried thereon, and such shaking movement is imparted to the front end of the forming wire which is passing over the breast-roll. Owing to the width of the forming wire, and the rigidity inherent therein, it is apparent that a certain amount of the shaking movement which is imparted to the forming wire by the breast-roll 21 will be transmitted to parts of the forming wire adjacent the breast-roll end which are at the moment passing over the table rolls 26 at the forward end of the machine. During such shaking movement of the forming wire, the forming wire of course slides over the table rolls, the extent of the shake and hence the extent of such sliding decreasing at points progressively farther removed from the breast-roll 21. The length of the shaking zone or area over the table rolls 26 of course depends largely upon the amplitude of shake transmitted to the forming wire by the breast-roll 21 and the characteristics of the forming wire, such as its weight and rigidity. It has been found, however, that by shaking only the breast-roll, and with wires of normal construction, the length of the shaking zone is adequate to secure a satisfactory felting of the paper being formed.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a paper-making machine, a forming section of the Fourdrinier type comprising a shakable breast-roll including a support

therefor, a normally stationary frame carrying thereon table rolls and save-alls, said frame being supported independently of said breast-roll and in alignment therewith, and 5 means carried by said breast-roll support and shakable therewith for deflecting fluid matter from the breast-roll to said save-alls.

2. In a paper-making machine, a forming section of the Fourdrinier type comprising 10 a shakable breast-roll including a support therefor, a normally stationary frame carrying thereon table rolls and save-alls, said frame being supported independently of said breast-roll and in alignment therewith, and 15 a doctor for said breast-roll adjustably secured to said breast-roll support and shakable therewith, said doctor having provisions for deflecting fluid matter from the breast-roll to said save-alls.

20 3. In a paper-making machine, a forming section of the Fourdrinier type comprising a breast-roll, a support for the breast-roll, said breast-roll being removably mounted in bearing carried by said support, a table-roll frame in alignment with said breast-roll, a forming wire mounted on said breast-roll and adapted to cooperate with the rolls of said table-roll frame, means carried by the table-roll frame adapted to temporarily support said breast-roll, means adapted to guide the breast-roll from its bearings into position for engagement with said temporary supporting means, and means for bodily moving said frame and the temporarily supported breast-roll out of alignment with said wire to facilitate removal of the wire.

4. In a paper-making machine, a forming section of the Fourdrinier type comprising a breast-roll, a support for the breast-roll, 40 said breast-roll being removably mounted in bearings carried by said support, a table-roll frame in alignment with said breast-roll, a forming wire mounted on said breast-roll and adapted to cooperate with the rolls of said table-roll frame, means for bodily moving said frame out of alignment with the breast-roll to facilitate removal of the wire, and means for transferring the breast-roll from its normal bearings to said frame for 45 movement with the latter out of alignment with the wire, said last-mentioned means including breast-roll supporting means carried by the frame, guide means for guiding the breast-roll from its bearings into position for engagement with said supporting means and vice versa, and hoisting means for controlling movement of the breast-roll along the guiding means.

5. In a paper-making machine, a forming 60 section of the Fourdrinier type comprising a breast-roll, supports therefor, a table-roll frame in alignment with the breast-roll, an independent suction-box frame also in alignment with the breast-roll, a forming wire mounted on the breast-roll and adapted to

70 pass over the table-roll frame and the suction-box frame, and means for bodily moving said frames out of alignment with the breast roll supports to facilitate removal of the wire.

6. In a paper-making machine, a suction-box frame carrying suction boxes over which a forming wire is adapted to move, supporting means for said suction-box frame constructed and arranged to permit bodily 75 movement of the frame laterally out of alignment with the forming wire to facilitate removal of the latter, and means for oscillating the suction-box frame in a direction transverse to the moving forming wire, said last-mentioned means including a prime mover and driving connections so constructed and arranged as to permit lateral bodily movement of the suction-box frame.

7. In a paper-making machine, a forming 80 section of the Fourdrinier type comprising a breast-roll, supports therefor, a table-roll frame in alignment with the breast-roll supports, an independent suction-box frame also in alignment with the breast-roll supports, a forming wire mounted on the breast-roll and adapted to pass over the table-roll frame and the suction-box frame, and means for bodily 85 moving each of said frames out of alignment with the breast-roll supports to facilitate removal of the wire, said means including laterally extending rails adapted to guide the lateral movement of the said frames.

8. In a paper-making machine, comprising 90 a forming section of the Fourdrinier type having a forming wire, a breast-roll receiving said forming wire, a table-roll frame in alignment with the breast-roll, an independent suction-box frame also in alignment with the breast-roll, and means for bodily moving 95 said suction-box frame out of alignment with the wire to facilitate replacement of the wire.

9. In a Fourdrinier paper machine, a 100 breast-roll, supports therefor, and a doctor adjustably secured to said supports for coaction with said breast-roll.

10. In a Fourdrinier paper machine, a 105 breast roll, supports therefor, removable bearing sections for said breast roll mounted on said supports, and a doctor pivotally supported from said bearing sections for coaction with said breast roll.

11. In a Fourdrinier paper machine, a 110 breast roll, supports therefor, removable bearing sections for the journals of said breast roll mounted on said supports, a doctor for coaction with said breast roll and adjustable arms pivotally secured to said bearing sections for supporting said doctor. 115

12. In a Fourdrinier paper machine, a 120 breast roll, supports therefor, a table section including table rolls and save-alls independently formed from said breast roll supports, a doctor for said breast roll for de- 125

- flecting fluid matter from the breast roll into a save-all and means for shaking said breast roll independently of the table section.
13. In a Fourdrinier paper machine, a breast roll, a support having removable bearings to receive the journals of said breast roll, a table section in alignment with said breast roll, means carried by said table section for temporarily supporting said breast roll, guide means for guiding the breast roll from its bearings into position for engagement with said supporting means and hoisting means for controlling the movement of said breast roll along the guiding means.
14. In a Fourdrinier paper machine, a breast roll, a support having removable bearings to receive the journals of said breast roll, a table section in alignment with said breast roll, means carried by said table section for temporarily supporting said breast
- 5 10 15 20
- roll, guide means for guiding the breast roll from its bearings into position for engagement with said supporting means, hoisting means for controlling the movement of said breast roll along the guiding means, and means for removing said table section together with said breast roll laterally of the machine out of alignment with said breast roll supports.
15. In a Fourdrinier paper machine, a breast roll, supports therefor, a table section, means for temporarily supporting said breast roll from said table section, guides for guiding said breast roll into position for engagement with said supporting means and hoisting means for controlling the movement of said breast roll along said guiding means.

In testimony whereof I hereto affix my signature.

HERMAN L. KUTTER.
